UNITED STATES PATENT OFFICE.

OTTO H. HERTEL, OF GLENELLYN, ILLINOIS, ASSIGNOR, BY MESNE ASSIGNMENTS, TO KREHBIEL COMPANY, OF CHICAGO, ILLINOIS, A CORPORATION OF ILLINOIS.

AUTOMATIC AIR CONTROL FOR FURNACES.

1,358,204.

Specification of Letters Patent.

Patented Nov. 9, 1920.

Application filed February 1, 1918. Serial No. 214,813.

To all whom it may concern:

Be it known that I, OTTO H. HERTEL, a citizen of the United States, and a resident of Glenellyn, in the county of DuPage and

5 State of Illinois, have invented certain new and useful Improvements in Automatic Air Control for Furnaces, of which the following is a specification.

10 My invention relates to improved automatic air controlling mechanism for furnaces.

15 In my co-pending application Serial No. 203,231, filed November 21, 1917, I disclose a two-zone furnace comprising a zone for receiving and coking coal and another zone for receiving the coke from the coking zone and burning it, and separate ash pits for the grate sections of the zones together with air inlets to the pits. The object of my present

20 invention is to provide automatically operated mechanism for controlling the supply of air into the ash pits and to the respective grates of the zones.

On the accompanying drawings—

25 Figure 1 is a side elevational view, partly in section, showing one form of furnace to which my invention is applied.

Fig. 2 is an enlarged sectional view on plane 2—2, Fig. 1,

30 Fig. 3 is a perspective view of the air controlling mechanism for the coke burning zone, and

Fig. 4 is a fragmentary view showing another position of the parts shown in Fig. 2.

35 In the furnace shown the combustion chamber is divided by a transversely extending wall or arch 12 into a forward coking zone and a rearward combustion zone 11, said arch terminating a short distance above the grate 13 and forming a passageway 14 for the passage of the coke from the coking zone to the combustion zone. Below the zone 10 is the ash pit 15 and below the zone 11 is the ash pit 16, these ash pits

40 being separated by the wall 17. The ordinary form of door 18 is provided for the ash removing opening 19 of the pit 15, the door having the air passageway 20 to be controlled by the damper 21 pivoted to swing vertically.

A rectangular frame 22 is secured to one side of the pit 16 around a suitable opening therethrough and has hinged thereon the door 23 for controlling such opening for the removal of ashes. The door has the 55 rectangular opening 24 which is controlled by the damper 25, the damper shown being in the form of a rectangular plate from the centers of whose sides extend pivot pins 26 and 27 which are journaled in fittings 28 and 29 secured to the ash door 23. Within the opening 24 is seated a rectangular abutment frame for the damper comprising the upper and lower horizontal walls 30 and 31 and the triangular side wall sections 32, 33 and 34, 65 35, the pivot line of the damper being substantially at the apexes of the side walls. The dimensions are such that when the damper is swung to one extreme position it will close the air passageway by engaging 70 against the inner and outer edges respectively of the walls 30 and 31 and against the inner edges of the side wall sections 32 and 34 and the outer edges of the side wall sections 33 and 35, as shown in full lines Fig. 2. 75 When the damper is in its other extreme position, as shown in dotted lines Fig. 2, it will engage with the opposite edges of these walls to completely close the air passageway.

Extending laterally from the corner of the damper is a pin 36, and pivoted at its inner end to the side wall 35 is the operating lever 37 which has the longitudinally extending slot 38 for receiving the pin. The inner end 80 of the longitudinal slot communicates with the upper end of the transverse slot 39 in the lever. When the pin is within the longitudinal slot and the lever is swung vertically the damper will be rotated to control the 85 air passageway, and the location of the transverse slot 39 is such that when the lever is swung downwardly sufficiently to entirely close the damper the pin will be within the transverse slot so that the lever can then be 90 raised without carrying the damper with it (see dotted lines Fig. 2).

Pivoted to the side wall 35 below the operating lever 37 is a latch bar or plate 40 which at its outer end has the transversely 100

extending slot 41. The slot extends diagonally and its lower end is at such distance from the pivot point of the latch that when the latch is raised while the damper is closed 5 the upper edge of the latch will engage with the pin 36 and raise the damper until the slot receives the pin. The latch and the damper will thus be locked together and the damper will be held partly open.

10 For automatically controlling the damper 25 and the damper 21 ordinary diaphragm mechanism may be used. As shown, the diaphragm surrounding frame 42 is mounted on top of the furnace and connected by pipe 15 43 with the boiler 44. A stem 45 extends upwardly from the diaphragm (not shown) within the frame and is connected with the lever 46, which lever is pivoted intermediate its ends on the bracket 47 extending from 20 the frame 42. A chain 48 connects one end of the lever with the outer end of the operating lever 37, while a chain 49 connects the other end of the lever 46 with the damper 21, the chain 49 being guided by suitable pulleys 50.

25 The operation of the mechanism is as follows:

Assume that the furnace is cold and the fire is to be started. There being no steam 30 pressure the right end of the diaphragm mechanism lever 46 will be held down by the weight W and the operating lever 37 will be down and the damper 25 closed. The other end of the lever 46 being up, the damper 21 will be held up to open the air inlet passageway 20. The operator now charges green fuel into the zone 10 and ignites it. The damper below the coke burning zone 11 being closed and the damper 35 21 under the coking zone being open, the draft of the chimney 51 will cause air to be drawn into the ash pit 15, through the grate 13 into the zone 10, and from there into the zone 11 through the passageway 14 or through the passageway 52 in the wall 40 12, which passageway may be controlled by a damper 53. The air flow being concentrated on the green fuel, this fuel will burn rapidly and quickly produce coke. 45

45 As soon as coke is formed the operator inserts a bar through the fuel charging opening 54 and pushes the coke through passageway 14 into the coke burning zone 11. As it will take some time to generate enough 50 steam pressure to operate the diaphragm mechanism the operating lever 37 will be down with its transverse slot 39 receiving the pin 36 of the closed damper 25 Fig. 2. However, as soon as the operator shifts 55 coke into the zone 11 he raises the latch 40 to receive the pin 36 in the notch 41 thereby to partly open the damper 25 and to shift the pin 36 a short distance into the longitudinal slot 38 of the operating lever, as

shown in Fig. 4. After such setting the 65 mechanism is ready for automatic operation. The partial opening of the damper 25 permits sufficient air to keep up combustion of the coke charged into the zone 11 and as the steam pressure rises the diaphragm lever 46 will be rotated to drop the damper 21 and to raise the operating lever 37 to swing the damper 25 toward horizontal position, during which horizontal position the air passageway to the pit 16 will be fully 70 opened. As soon as the operating lever 37 is raised it will draw the pin 36 out of the slot 41 of the latch 40, and this latch being loosely pivoted, will drop. The furnace is now in normal operation, the steam pressure 75 controlling the degree of opening or closure of the respective dampers. Should the furnace generate too much heat, the increased steam pressure will further close the damper 21 and will raise the damper 25 above its 80 horizontal position of maximum opening to reduce the air passageway to the pit 16, and to eventually fully close both dampers. As soon as the heat is reduced and the steam pressure drops the dampers are again opened 85 and so long as the operator will at proper times supply fuel and shift the generated coke from the zone 10 into the zone 11 the furnace will be automatically controlled.

90 However, should the operator neglect the 95 furnace and forget to push coke into the zone 11, the heat generation by the furnace will diminish and the steam pressure will drop and the automatic mechanism will lower the damper 25 and open the damper 21, and this continues until the operating lever 37 has dropped sufficiently to entirely 100 close the damper 25 and the damper 21 has been opened wide. The lever 37 being down and the damper 25 fully closed, the pin 36 105 will again be in the transverse slot 39 so that when the lever 37 is again raised it will be released from the damper 25. The entire draft of the furnace is now through the wide open air passageway 20 and through 110 the coking zone and so long as no coke is being pushed into the zone 11 all the heat is generated in the zone 10, and even though the steam pressure rises and the automatic mechanism raises the operating lever 37 the 115 damper 25 will remain closed and only the damper 21 operated to control the air supply in accordance with the steam pressure. When the operator sees that the lever 37 is released from the damper 25 he knows 120 that there is no fuel in the coke burning zone and he therefore attends to the fire by pushing coke back into the zone 11 and causing re-connection of the damper 25 with its operating lever.

125 I do not of course desire to be limited to the exact construction, arrangement and operation shown and described as changes

and modifications are no doubt possible which would still come within the scope of the invention.

I claim as follows:

- 5 1. In a furnace, the combination of two combustion zones, a separate ash pit for each zone, an air inlet for each ash pit, a damper hinged at one end to control the air inlet for one of said ash pits, a damper 10 trunnioned within the inlet for the other ash pit to be swung to extreme positions to close said inlet or to intermediate positions to open said inlet, a pin extending from said trunnioned damper, a lever pivoted adjacent said trunnioned damper and having a slot for receiving said pin whereby said damper is rotated when the lever is swung, said lever having a transverse slot at the end of the longitudinal slot, said transverse 15 slot receiving the pin when said trunnioned damper is in one position of closure whereby said lever may then be raised independently of said damper, a prop for normally holding said trunnioned damper partially 20 open to shift the pin out of the transverse slot and into the longitudinal slot, and means automatically controlled in accordance with the heat generated by the furnace and connected with said lever and said first 25 mentioned damper to automatically control the opening and closure of said dampers.
2. In a furnace, the combination of two zones in which fuel may be burned, grate surface below each zone, an ash pit below each zone, each pit having an air inlet, chimney draft normally effective on both zones, damper mechanism normally controlling both air inlets in accordance with the combined heat delivered by said zones, 30 and means for closing one inlet and opening the other when the fire in one zone dies out whereby the chimney draft will be then concentrated on the other zone.

3. In a furnace, the combination of a coking zone and a burning zone in which the coke formed in the coking zone is received and burned, chimney draft normally effective on both zones, and means controlled by the heat delivered by said furnace for concentrating the chimney draft on the coking zone when the fire in the burning zone dies down.

4. In a furnace, the combination of a coking zone and a burning zone for receiving and burning the coke formed in the coking zone, chimney draft connected with said zones, an air inlet for each zone, and means controlled by the heat delivered by said zones for automatically closing the air inlet for the burning zone to thereby concentrate the chimney draft on the coking zone which zone then becomes the burning zone.

5. In a furnace, the combination of a coking zone and a coke burning zone, there

being a passageway between said zones for the shifting of coke from the coke forming zone to the coke burning zone, an outlet from said coke burning zone to a chimney, independent air inlets for each zone, means automatically controlled by the heat delivered by said zones for normally opening and closing said air inlets in accordance with the heat delivered whereby both zones are subject to the chimney draft, said air inlet controlling means causing closure of the air inlet for the burning zone when the fire in said zone dies down, whereby the chimney draft is then concentrated on the coking zone and said zone becomes the burning zone.

6. In a furnace, the combination of two zones, chimney draft connected with said zones, independent air inlets for said zones, damper mechanism for each inlet, means automatically controlled by the heat delivered by said zones for controlling the operation of said dampers, said damper controlling mechanism operating when the fire in one zone becomes low to close the inlet damper for said zone and to disconnect it from said damper whereby the chimney draft is then concentrated on the other zone and the inlet damper for said other zone controlled by said damper controlling mechanism.

7. In a furnace, the combination of two zones, independent air inlets for said zones below the grate thereof, chimney draft connected with both zones, damper mechanism for each air inlet, thermostat mechanism normally connected with both damper mechanisms to control the opening and closure thereof in accordance with the heat delivered by said zones, and means for automatically disconnecting the damper mechanism of one zone from said thermostat mechanism when the fire in said zone dies down.

8. In a furnace, the combination of a coking zone and a coke burning zone, there being a passageway between said zones for the transfer of coke from the coking zone to the coke burning zone, and means automatically controlled by the heat delivered by said zones for closing the draft for the coke burning zone and increasing the draft on the coking zone when the supply of coke in said coke burning zone is exhausted.

9. In a furnace, the combination of two zones, draft producing means, means for normally connecting said draft producing means with both zones, and means for disconnecting said draft producing means from one zone when the fuel in said zone is exhausted and to concentrate the draft on said other zone.

10. In a furnace, the combination of a coking zone and a coke burning zone, independent air inlets for said zones below the

grate surfaces thereof, damper mechanism for each air inlet, thermostat mechanism connected with said damper mechanism and controlled by the heat delivered by said zones, said thermostat mechanism automatically controlling the degree of opening or closure of said damper mechanism during normal operation of the furnace, and means for disconnecting the coke burning zone in-

let damper mechanism from said thermostat mechanism when said damper mechanism has been closed and the damper mechanism for the coking zone fully opened.

In witness whereof, I hereunto subscribe my name this 26th day of January, A. D. 1918.

OTTO H. HERTEL.
